DESIGN FOR AN EMBLEM KEY

Charles F. Cwazka, Jackson Heights, N. Y.

Application August 26, 1935, Serial No. 58,295

Term of patent 7 years

To all whom it may concern:

Be it known that I, Charles F. Cwazka, a citizen of the United States, residing at Jackson Heights, Long Island, in the county of Queens and State of New York, have invented a new, original, and ornamental Design for an Emblem Key, of which the following is a specification, reference being had to the accompanying drawing, forming part thereof.

In said drawing, Figure 1 is a face elevation, and Figure 2 is a side edge elevation of an emblem key, showing my new design.

I claim:

The ornamental design for an emblem key as shown.

CHARLES F. CWAZKA.
